US00D692004S

(12) **United States Design Patent**
Man

(10) **Patent No.:** US D692,004 S
(45) **Date of Patent:** ** Oct. 22, 2013

(54) **BARCODE SCANNER AND RADIO
FREQUENCY IDENTIFICATION READER
COMBO**

(71) Applicant: **Megaviz Limited**, Hong Kong (HK)

(72) Inventor: **Chun Sing Matthew Man**, Hong Kong (HK)

(73) Assignee: **Megaviz Limited**, Hong Kong (HK)

(**) Term: **14 Years**

(21) Appl. No.: **29/446,023**

(22) Filed: **Feb. 20, 2013**

(30) **Foreign Application Priority Data**

Aug. 31, 2012 (HK) 1201739.2

(51) **LOC (9) Cl.** **14-02**

(52) **U.S. Cl.**

USPC **D14/428**; D14/426

CLAIM

The ornamental design for a barcode scanner and radio frequency identification reader combo, as shown and described.

DESCRIPTION

FIG. 1 is a perspective view of a barcode scanner and radio frequency identification reader combo of my new design; FIG. 2 is a front view of the barcode scanner and radio frequency identification reader combo thereof;

FIG. 3 is a rear view of the barcode scanner and radio frequency identification reader combo thereof;

FIG. 4 is a top view of the barcode scanner and radio frequency identification reader combo thereof; and,

FIG. 5 is a left view of the barcode scanner and radio frequency identification reader combo thereof.

1 Claim, 5 Drawing Sheets
